CARTON FEEDING APPARATUS FOR
ARTICLE CARTONING MACHINES

Grover C. Currie, Bernard D. Dans, Louis F. Wilkens, and Maurice B. Dunn, Charlotte, N. C., assignors to Dacam Corporation, Charlotte, N. C., a corporation of North Carolina

Application June 25, 1951, Serial No. 233,414

14 Claims. (Cl. 53—91)

1

This invention relates to machines for receiving bottled beverages, placing the same in a carton, sealing the carton and delivering the filled carton from the machine, and more especially to an improved apparatus for positively feeding the cartons into the machine so as to be accurately positioned for receiving the bottled beverages relative to other moving parts of the machine regardless of the speed of the machine.

The improved apparatus for feeding the cartons into the machine is particularly adapted for use with a machine of the type shown in the co-pending application of Grover C. Currie et al., Serial No. 788,602, filed November 28, 1947, and entitled Means for Placing Articles in Cartons, now Patent No. 2,603,924.

The machine embodied in said co-pending application is of a type to which filled bottles, cans or other containers are delivered from a bottling machine or the like and the machine will then position open-bottomed cartons at a predetermined point and means are provided for opening the sides of the carton apart from each other and then other means are provided for raising a group of bottles up into the carton. The cartons and bottles are then held in elevated position while the elevating means is moved away from the lower surface of the bottles. Then, the bottom flaps of the carton are moved to horizontal position against the bottoms of the bottles, in which position they are secured and the carton filled with bottles is delivered onto an endless conveyor for discharging the same from the machine.

Now, in the machine embodied in said co-pending application, the cartons have been stacked in a magazine from which the cartons were moved, one at a time, to a position immediately above the means for opening the sides of the carton apart from each other, after which the last-named carton was rotated from a horizontal to a vertical position and then permitted to move, by gravity, downwardly to a position between said means for opening the sides of the carton apart from each other to receive the group of bottles raised into the carton. However, the means described for positioning the cartons one at a time between the means for opening the sides of the cartons apart from each other has necessarily limited the speed at which the machine could be operated due to the cartons usually being of a relatively light material and as a result of which the speed at which the carton is moved downwardly, by gravity, could not be controlled. Consequently, in the event of the speed of the

2

machine being substantially increased, the carton would not be properly positioned between the means for opening the sides of the carton apart from each other in proper timed relation to the operation of the means for opening the sides of the carton apart from each other.

It is, therefore, an object of this invention to provide a positive means for feeding the cartons to the means for opening the sides of the carton apart from each other and wherein said positive means operates in accurately timed relation to the various other moving parts of the machine to thus insure that each successive carton is properly positioned for reception of the bottles which are subsequently raised thereinto.

More specifically, it is an object of this invention to provide an apparatus of the type described comprising a hopper or magazine disposed above and to one side of the vertical plane 20 of the means for opening the sides of the carton apart from each other and said hopper being adapted to contain a stack of superposed cartons therein and having means for directing the lowermost of the cartons in the hopper, one at 25 a time, onto a carton positioning plate or platform which is pivotally mounted on the machine.

There is also an oscillatable carton edge gripping or grasping device which is disposed adjacent the edge of the platform remote from the 30 magazine and which is in a normally open position as the carton is moved to the platform and means are provided to operate in timed relation to the various other moving parts of the machine which will cause the grasping or gripping device to clamp the corresponding edge of the carton and to simultaneously rotate the carton about the axis of the grasping device.

Moreover, at the time the carton is rotated, the platform is rotated automatically about its axis disposed to one side of the grasping device to thus permit the carton to be revolved from a horizontal to a vertical position. Upon the carton being revolved to a vertical position, the grasping device is then moved downwardly by a 40 mechanical means and, upon moving downwardly to a predetermined position adjacent the means for opening the sides of the carton apart from each other, the grasping device then releases the carton and returns to its original position whereupon, said last-named means operates in the manner described in said Patent No. 2,603,924 to move the opposed sides of the carton apart from each other for the reception of the bottles or other articles raised thereinto.

55 Some of the objects of the invention having

been stated, other objects will appear as the description proceeds when taken in connection with the accompanying drawings, in which—

Figure 1 is a front elevation of the bottle cartoning machine showing the improved apparatus for positively feeding the cartons to the means for opening the sides of the carton apart from each other mounted thereon;

Figure 2 is a side elevation looking at the left-hand side of Figure 1 with many of the parts being omitted and other parts being shown in section for purposes of clarity;

Figure 3 is an enlarged top plan view looking down at the top of Figure 1 but omitting many of the parts which are disposed at the lower portion of the machine shown in Figure 1;

Figure 4 is an enlarged detail view of the central left-hand portion of Figure 5 taken substantially along the line 4—4 in Figure 1;

Figure 5 is an enlarged vertical sectional view taken substantially along the line 5—5 in Figure 1 with many of the parts being shown schematically and showing the grasping device in an intermediate position;

Figure 6 is a fragmentary elevation of the lower actuating means for the carton edge grasping device and is taken substantially along the line 6—6 in Figure 4;

Figure 7 is an enlarged elevation of the grasping device shown in the upper left-hand portion of Figure 5 but showing the grasping device in an elevated position;

Figure 8 is a top plan view with parts in section taken substantially along the line 8—8 in Figure 7;

Figure 9 is an enlarged fragmentary vertical sectional view with parts broken away taken substantially along the line 9—9 in Figure 1 and showing a part of the means for opening and closing the jaws of the grasping device which is instrumental in moving the cartons downwardly to a position between the device for moving the sides of the carton apart from each other;

Figure 10 is an enlarged fragmentary vertical sectional view taken substantially along the line 10—10 in Figure 3;

Figure 11 is an isometric view looking substantially in the direction of the arrow 11 in Figure 5 and showing the manner in which the hopper for the cartons is constructed;

Figure 12 is an isometric view of the grasping device showing the top thereof and the right-hand end thereof as shown in Figure 8.

Inasmuch as those parts of the machine other than the improved apparatus for positively feeding the cartons to a predetermined position are substantially the same as those described in said Patent No. 2,603,924, only those parts of the machine which are particularly pertinent to the present invention will be described in detail.

Referring more specifically to the drawings, the numeral 10 broadly designates the frame of the machine which includes left-hand and right-hand vertically disposed side frame members 11 and 12, respectively, which are shown as being of cast construction.

The front and rear portions of the upper ends of the side frame members 11 and 12 are bridged by respective horizontally disposed frame members 13 and 14, the lower front portions thereof being bridged by a horizontally disposed frame member 15. There are also disposed between the side frame members 11 and 12, intermediate transverse frame members 16, 17, 18 and 19, the frame members 15 to 19, inclusive, being sub-

stantially the same as those shown in said patent and being suitably secured to the side frame members 11 and 12 at opposed ends thereof.

It will be observed in Figures 1 and 2 that the side frame members 11 and 12 are suitably secured to the upper surface of a base member 25. These side frame members have bearing blocks 26 suitably secured to the front surfaces thereof (Figure 1) in which a driven cam shaft 27 is rotatably mounted, this cam shaft 27 may be driven in the manner shown in said patent.

In order to avoid confusion, many of the cams are omitted from the cam shaft 27 and only those which are pertinent to the present invention are shown mounted on the cam shaft 27. However, it is to be understood that the cams shown in said patent mounted on the cam shaft may also be included on the cam shaft 27 shown in Figures 1, 2 and 5.

As is clearly described in said patent, the cartoning machine includes an endless conveyor designated generally at C onto which filled bottles, cylindrically-shaped cans or other articles are delivered from a bottling or canning machine or the like. The endless conveyor C is mounted on a pair of sprocket wheels 30 which are fixedly mounted on a transverse shaft 31 rotatably mounted in bearing blocks or stands 32 which project outwardly and are suitably secured, as by screws 33, to the transverse frame member 15 (Figures 1 and 5). This shaft 31 may be driven in the manner shown in said patent.

The filled bottles, cans or the like, which will hereinafter be referred to as articles, are moved along by the conveyor C and are subsequently positioned in side-by-side relation on a vertically movable platform or elevator 35 which is provided with means for raising the same, as is clearly shown in said patent, and to thus position the group of articles carried thereby between the proximate faces of a pair of transversely spaced grasping devices or units 36 and 37 which are provided with suitable suction means on the proximate faces thereof for moving the opposed sides of a carton C-1 apart from each other after the carton C-1 has been positioned therebetween, in a manner to be later described, and before the elevator 35 has moved upwardly to position the group of articles between the grasping devices 36 and 37, with the result that the articles are then moved upwardly into the carton supported by the grasping devices 36 and 37.

The carton C-1 may be of the type shown in the co-pending application of Grover C. Currie et al., Serial No. 788,603, filed November 28, 1947, now U. S. Patent No. 2,556,069, and entitled Bottle Carton.

After the articles are positioned between the opposed sides of the carton C-1, the grasping devices 36 and 37 move inwardly to urge the opposed sides of the carton inwardly against the articles disposed therebetween and to thus clampingly support the articles and the carton C-1 while a pair of folding members 40 and 41 are moved inwardly beneath the articles in the carton by conventional means, not shown, and, in so doing, these folding members 40 and 41 engage and fold the bottom flaps of the carton C-1 beneath the articles disposed between the sides of the carton C-1.

Now, since at least one of the flaps on the lower portion of the carton C-1 is provided with an adhesive, upon the folding members 40 and 41 moving into position beneath the articles in

the carton C-1, the bottom flaps of the carton are caused to adhere to one another.

The grasping devices 36 and 37 move apart from each other slightly following the movement of the folding devices or members 40 and 41 to a position beneath the articles in the carton C-1 so as to permit the carton to be slid off of the folding members 40 and 41 by a plunger 42 which is operated by conventional means in timed relation to movement of the folding members 40 and 41 to a position beneath the articles in the carton C-1 and this plunger moves the filled carton C-1 off of the folding members 40 and 41 onto a suitable conveyor or other means for discharging the filled carton from the machine. This plunger 42 is mounted for horizontal sliding movement in a guide member 43 which is suitably secured, as by screws 44 (Figure 4) to the transverse frame member 16.

After the filled carton C-1 has been slid off of the folding members 40 and 41, the folding members 40 and 41 move apart from each other to their original position to complete a cycle in the machine as originally designed. It is in association with a machine of the type heretofore described that the present invention is particularly adapted to be associated.

The hopper, which is broadly designated at 50, may be identical to the hopper shown in said Patent No. 2,603,924 or as shown in the present drawings. This hopper 50 comprises a front wall including a pair of vertically disposed and laterally spaced bars 51 which are suitably secured, as by screws 52 (Figure 5) to a transverse bar 53. The hopper 50 also comprises a rear wall including a pair of vertically disposed and laterally spaced bars 55 which are suitably secured intermediate their ends, as by screws 56, to another transverse bar 57. Opposed ends of the transverse bars 53 and 57 are suitably secured, as by respective bolts 60 and 61 to the upper surfaces of respective portions 62 and 63 which are integral parts of laterally spaced brackets designated broadly at 65 (Figure 3).

It is most clearly shown in Figure 11 that the portion 62 of each of the brackets 65 is in the shape of a letter T and the portion 63 of each of the brackets 65 extend rearwardly from the lower end of the shank of the T-shaped portion 62 and then upwardly at an angle and again rearwardly and has a longitudinally extending slot 66 therein which is penetrated by the corresponding bolt 61 to thus permit the bar 57 and the corresponding vertically disposed bars 55 to be adjusted forwardly and rearwardly for varying the displacement between the bars 55 and the bars 51 according to the size of the cartons adapted to be stacked in the hopper 50. The laterally spaced brackets 65 are suitably secured, as by bolts 67 (Figure 11) to the upper surface of the transverse frame member 14 heretofore described.

This transverse frame member 14 also supports a bottom plate 70 which serves as the bottom to the hopper 50 and on which the lowermost of the cartons in the hopper 50 is adapted to rest. Side walls 72 and 72' of the hopper 50 are shown in the form of vertically disposed laterally spaced plates and the medial portions of these side wall plates 72 and 72' are suitably secured, as by welding (Figures 3 and 11), to the proximate ends of substantially L-shaped brackets 73 and 73'.

The horizontal legs of the brackets 73 and 73' are slotted, as at 74 and 74' and these slots are penetrated by respective screws 75 and 75'

for securing the respective brackets 73 and 73' to the upper surfaces of the T-shaped portions 62 of the corresponding brackets 65.

It is thus seen that the side wall plates 72 and 72' may be adjusted relative to each other and that the bar 57, to which the vertically disposed bars 55 are secured, may be adjusted forwardly or rearwardly to thus accommodate cartons of various sizes.

10 The bottom plate 70 is provided with a pair of laterally spaced slots 77 and 77' in which corresponding carton ejecting blocks 80 and 80' have freedom of movement forwardly and rearwardly of the machine. The blocks 80 and 80' have respective pusher plates or bars 81 and 81' suitably secured thereto, as by screws 78. The leading edges of the pusher bars 81 and 81' project upwardly from the corresponding blocks 80 and 80' and their leading edges are also spaced rearwardly of the tapering leading edges of the corresponding blocks 80 and 80' (Figure 5).

The blocks 80 and 80' are suitably secured, as by welding, to the opposed ends of a laterally extending support bar 82 which is suitably secured, as by screws 83 (Figure 3), only one of which is shown, to the upper surface of a carrier block 84 which is shown as being dovetailed for forward and rearward sliding movement on a dovetailed guide bar 85. The guide bar 85 is suitably secured, as by screws 86, to the lower surface of the transverse frame member 14 heretofore described.

One end of a link 90 is pivotally connected, as at 91 (Figures 5 and 11) to one side of the carrier block 84. This link 90 extends forwardly and is pivotally connected, as at 92, to one end of crank arm 93 which is fixedly mounted on a transverse shaft 94. The transverse shaft 94 extends substantially half the distance between the frame members 11 and 12 and is supported at one end thereof in the frame member 11 and its medial portion is oscillatably mounted in a bracket 95 depending from and being suitably secured to the lower surface of the transverse frame member 14.

The crank arm 93 has a slot 96 therein in which a pin 97 has longitudinal sliding movement. The pin 97 is fixedly secured in one end of a longitudinally adjustable connecting rod or link 100 which is pivotally connected, as at 101, to an arm 102 extending substantially radially from a sleeve 103 oscillatably mounted on a stub shaft 104 (Figures 5 and 11) which is fixed at one end thereof in a forwardly projecting portion 105 integral with the bracket 95 heretofore described.

As is most clearly shown in Figures 5 and 11, the sleeve 103 has a plate 106 suitably secured thereto, as by screws 107, only one of which is shown in Figure 5 and these screws 107 penetrate suitable tab portions integral with the plate 106. This plate 106 has a pair of carton positioning arms 110 suitably secured thereto and normally projecting upwardly therefrom as shown in Figure 5. These arms 110 are secured to the plate 106 by any suitable means such as screws 111. The bottom plate 70 is provided with suitable longitudinally extending slots 112 at the front edge thereof (Figure 3) which are loosely penetrated by the arms 110. The function of these carton positioning arms 110 will be later described.

Now, referring to Figures 1 and 2, it will be observed that the shaft 94 extends outwardly beyond the side frame member 11 and has a crank arm 113 fixedly mounted thereon to the free end of which

a link 114 is pivotally connected, as at 115. This link 114 extends downwardly and is pivotally connected, as at 116, adjacent one end of a lever arm 117. The lever arm 117 is oscillatably mounted on the side frame member 11, as at 120, and has a cam follower 121 on the end thereof remote from the end adjacent which the link 114 is pivotally connected. This cam follower 121 is normally urged into engagement with the peripheral surface of an irregularly shaped cam wheel 122 by a tension spring 123 which is connected at its lower end to the rear free end of the lever arm 117 and which is suitably connected at its other end, as at 124, to the side frame member 11 at a point spaced substantially above the lever arm 117.

It is thus seen that the cam 122, which is fixedly mounted on the driven cam shaft 27, will cause oscillation to be imparted to the shaft 94 in accordance with the configuration of the cam wheel 122. Thus, as the shaft 94 is caused to move in a counter-clockwise direction in Figures 5 and 11, the crank arm 93 will also move in a like direction thereby moving the carrier block 84 and the corresponding blocks 80 and 89 as well as the pusher plates 81 and 81' from right to left in Figures 5 and 11. The height of the free front end of the pusher plates 81 and 81' is such that they will engage only the lowermost carton disposed in the hopper 50 and will thus slide the same along the upper surface of the bottom plate 70, this plate extending substantially beyond the bars 51 which define the front wall of the hopper 50.

It will be observed in Figure 5 that the lower ends of these bars 51 are spaced slightly from the upper surface of the bottom plate 70 to thus provide space therebetween for passage of the lowermost carton in the hopper 50 therebetween. As the carton is slid along the plate 70, it moves into engagement with and between a pair of upper traction wheels 125 and a pair of lower traction wheels 126, only one of the lower traction wheels being shown in Figure 5.

The lower traction wheels 126 are fixedly mounted on a transverse shaft 127 which is rotatably mounted in the side frame members 11 and 12 and which is driven by conventional means substantially as shown in said Patent No. 2,603,924. Therefore, a detailed illustration and description of the manner in which the shaft 127 is driven is deemed unnecessary.

The upper traction wheels 125 are fixedly mounted on a transverse shaft 130 which is rotatably mounted in bearing blocks 131 (Figure 10) disposed inwardly of and adjacent the opposed side frame members 11 and 12. Each of the bearing blocks 131 is oscillatably mounted intermediate its front and rear ends, as at 132, in an upwardly extending portion 133 of a bracket 134.

The upper traction wheels 125 may be driven in any desired manner, such as by frictional contact with the lower traction wheels 26 or by means of the carton passing between the upper and lower traction wheels. The upper traction wheels 125 are normally urged downwardly in Figures 5 and 10 by a compression spring 137 associated with each of the brackets 134, and it will be observed in Figure 10 that the upper end of the compression spring 137 bears against the medial portion of the corresponding bearing block 131 and the lower end thereof bears against the bracket 134, the brackets 134 being provided with suitable cavities 137a for reception of the lower

ends of the corresponding compression springs 137.

The bearing blocks 131 as well as the brackets 134 extend rearwardly beyond the compression springs 137 and the brackets 134 are threadably penetrated by respective adjustment screws 138, the upper ends of which bear against the lower surfaces of the bearing blocks 131. These adjustment screws 138 are held in proper adjusted position by lock nuts 139.

It is thus seen that the compression spring 137 associated with each of the bearing blocks 131 normally urges the shaft 130 downwardly and the adjustment screws 138 prevent the rolls 125 and 126 from being moved apart from each other beyond a predetermined point.

It will be observed in Figure 5 that the upper surfaces of the bottom traction rolls 126 are disposed at a slightly higher elevation than the upper surface of the bottom plate 70 of the hopper 50 and it is evident that the plate 70 is provided with suitable openings through which the traction rolls 126 project. If so desired, there may be a suitable means provided for applying an adhesive material to one or more of the flaps of the open ended cartons adapted to be used with this machine. However, since this adhesive applying means is not a necessary part of the present invention, a detailed illustration and description thereof is deemed unnecessary. It might be stated, however, that the adhesive applying means may be identical to that shown in said patent.

The length of stroke of the pusher plates or bars 81 and 81' (Figures 3 and 5) is such that the lowermost carton disposed in the hopper 50 will be moved forwardly to be engaged by the upper and lower sets of traction wheels or rollers 125 and 126. The pusher plates 81 and 81' will then return to the position shown in Figures 3 and 5 while the traction wheels 125 and 126 will cause the corresponding carton to be moved forwardly beyond the front edge of the bottom plate 70 of the hopper 50 and onto a carton positioning plate 135 which normally rests in a horizontal position substantially as shown in Figure 3.

The carton positioning plate 135 is provided with a notch 136 at its front edge and the front edge of the plate 135 is reenforced by a pair of stop blocks or bars 135a which are suitably secured to the upper surface of the plate 135. The plate 135 is provided with transversely extending adjustment slots 140 which are penetrated by bolts 141 for securing a side guide member or bar 142 to the upper surface of the carton positioning plate 135 when the plate is in a horizontal or raised position.

In order to insure that the carton which is thrown forwardly by the upper and lower traction wheels 125 and 126 will remain in engagement with the upper surface of the carton positioning plate 135, there are spaced slightly above the plate 135 a pair of transversely spaced carton hold-down bars 143 which are turned upwardly at their rear ends to insure that the carton will pass therebeneath as it is thrown forwardly by the traction wheels 125 and 126. Each of these bars 143 is also bent upwardly at an angle at the front end thereof and is then bent again in a vertical manner and is suitably secured, as by a screw 145, to the rear surface of the transverse frame member 13. One of the bars 143 is disposed substantially midway of the plate 135 when said plate 135 is in elevated position and

the other of the bars 143 is disposed adjacent the free end of the plate 135 and has an angle bar 146 suitably secured thereto, as by welding, the horizontal flange of which serves to support the corresponding edge of the carton as the carton is thrown onto the plate 135 by the traction wheels 125 and 126.

It is thus seen that as the carton is thrown onto the carton positioning plate 135 by the traction wheels 125 and 126, the guide bar 142 serves to insure that the opposite edge of the carton, that is, the edge thereof having the flaps thereon, is positioned tightly against the vertical leg of the angle bar 146. Moreover, the bars 135a prevent the carton from being moved beyond a predetermined point as it is thrown onto the plate 135 by the traction wheels 125 and 126.

As the carton is positioned on the carton positioning plate 135, the leading edge of this carton is moved between the proximate surfaces of the jaws of a grasping device broadly designated at 150 and which will be later described in detail.

The plate 135 is suitably secured at one end thereof, as by screws 151, to the lower surface of a block 152 which is fixedly mounted on one end of a horizontally disposed stub shaft 153. The shaft 153 is oscillatably mounted in a bearing block 155 which is suitably secured, as by screws 156, to the lower surface of the transverse frame member 13. The stub shaft 153 also has a pinion 157 fixedly mounted thereon (Figures 1, 3 and 9), the hub of which is provided with a pair of diametrically opposed radially extending arms 160, one of which is adapted to engage the lower surface of a stop screw 161 when the pinion 157 and the shaft 153 are urged in a counter-clockwise direction in Figure 1 by means to be presently described. This will insure that the upper surface of the carton positioning plate 135 will be positioned in substantial alinement with the horizontal leg of the angle bar 146 as the carton is thrown onto the plate 135 by the traction wheels 125 and 126 (Figure 5).

The pinion 157 is engaged by a segmental gear 165 integral with a lever arm 166 which lever arm is oscillatably mounted, as at 167, on the side frame member 11. This lever arm 166 extends outwardly beyond the pivot point 167 and is pivotally connected, as at 170 to a cuff member 171 which is slidably penetrated by a vertically disposed rod 172. The upper end of the rod 172 has a pair of lock nuts 173 threadably mounted thereon and the lower end thereof threadably penetrates the upper end of a connecting rod 174 (Figures 1 and 2). The rod 172 also has a pair of lock nuts 175 threadably mounted on a medial portion thereof, these lock nuts 175 being spaced from the lower surface of the cuff member 171 and there being a suitable compression spring 176 surrounding the rod 172. The upper end of the compression spring 176 bears against the upper surface of the uppermost of the lock nuts 175.

The connecting rod 174 extends downwardly and is secured in the upper end of a yoke member 177 which straddles the driven cam shaft 21 and is mounted for sliding movement thereon. The medial portion of the yoke member 177 has a cam follower 180 thereon which is urged downwardly against the upper peripheral surface of a cam wheel 181 fixedly mounted on the cam shaft 21. The cam follower 180 is urged against the cam wheel 181 by a tension spring 182, the upper end of which is suitably secured, as at 183, to the upper end of the connecting rod 174 and 75

the lower end of which is suitably secured, as at 184, to the side frame member 11.

It is thus seen that the cam wheel 181 will cause the lever arm 166 to oscillate and upon the lever arm 166 being moved in a clockwise direction in Figure 1, the corresponding arm 160 on the hub of the pinion 157 will engage the lower surface of the adjustment screw 161 and this will prevent further clockwise movement of the lever arm 166. However, the rod 174 will be permitted to continue its upper movement until the cam follower 180 has been elevated by the highest point on the cam 181 and since the lever arm 166 will remain stationary for a part of this upward movement of the rod 174, the compression spring 176 will permit the rod 172 to move upwardly in the cuff member 171 thus overriding the lever arm 166. This insures that the upper surface of the carton positioning plate 135 may be accurately positioned in alinement with the upper surface of the horizontal leg of the angle bar 146 in Figure 1.

It is evident that, upon the lowermost point on the cam 181 moving into engagement with the cam follower 180, the lever arm 166 will be caused to move in a counter-clockwise direction in Figure 1 to a substantially vertical position thus moving the plate 135 away from the lower surface of the corresponding carton previously positioned thereon since this carton will then be supported by the grasping device 150 and the angle bar 146.

Carton edge grasping or clamping device

Now, as heretofore stated, as the carton is thrown forwardly onto the carton positioning plate 135, the front edge of the carton is positioned between the opened jaws of the carton edge grasping device 150. The lower stationary jaw of the grasping device, to be presently described, being positioned in the opening 136 provided in the front edge of the carton positioning plate 135. At this time, the carton edge grasping device 150 is disposed in substantially the position shown in Figure 7.

The carton edge grasping device 150 comprises a stationary jaw 190 which is suitably secured to the upper surface of a rearwardly extending substantially flat portion 191 of a cast bracket 192. It will be noted that the stationary jaw 190 is positioned in substantially the same horizontal plane as the carton positioning plate 135 when the carton edge grasping device 150 is in a raised position and this jaw 190 is then positioned in the notch 136 and extends in a horizontal plane.

The bracket 192 also has a downwardly extending flange portion or ear 192a integral therewith and an enlarged front end portion 193 integral therewith. This enlarged front end portion 193 is fixedly mounted on the rear end of a stub shaft 194 to which the bracket 192 is suitably secured, as by a dowel pin 195. This stub shaft 194 is oscillatably mounted in a vertically movable grasping device carrier block broadly designated at 196 and which is mounted for vertical sliding movement on a vertically disposed dovetailed guide bar 197 (Figures 5 and 8).

It will be noted in Figure 8 that the grasping device carrier block 196 is provided with a gib 200 which engages the front surface of the dovetailed guide bar 197 and, in this instance, the gib 200 has an upwardly extending portion 201 integral therewith (Figures 2, 6 and 7) from which a spring anchor pin 202 extends. This spring anchor pin 202 has the upper end of a tension spring 203 connected thereto. The tension spring 203 extends

11

downwardly and is connected to another spring anchor pin 204 which penetrates and is fixedly mounted in an arm 205 and on the outer end of which a follower roller 206 is rotatably mounted.

The arm 205 has an eccentrically located boss portion 207 integral therewith which is fixedly mounted on the outer or front end of the stub shaft 194, heretofore described, and which is secured thereon by any suitable means such as a set screw 210. The proximate ends of the boss portion 207 and the enlarged portion 193 of the respective arm 205 and the bracket 192 slidably and rotatably engage the front and rear surfaces of the grasping device carrier block 196 thus preventing endwise movement of the shaft 194 therein.

Referring again to the stationary jaw bracket 192, it will be observed in Figures 7 and 8 that the boss portion 193 thereof is straddled by forwardly extending portions 212 of an upper or movable jaw support bracket broadly designated at 213. These portions 212 are oscillatably mounted on a hinge pin or rod 214 which is fixedly mounted in the enlarged or boss portion 193 of the bracket 192. The movable jaw support bracket 213 extends rearwardly and has an upper or movable jaw which is shown in the form of a bar 215, suitably secured thereto, as by set screws 216, and corresponding lock nuts 217.

It will be observed in Figure 7 that the lower ends of the set screws 216 extend slightly beyond the corresponding surface of the movable jaw 215 so the lower ends of these screws 216 preferably engage the upper surface of the lower jaw 190 rather than the lower surface of the jaw 215 engaging the jaw 190 when the jaws are in closed position. Thus, when the jaws are in closed position and there is a carton disposed therebetween, the ends of the screws 216 will engage the corresponding portion of the carton at spaced points thus insuring the carton will be tightly clamped by the grasping device 150.

In order to insure that the carton is properly introduced to the jaws 215 and 190 of the grasping device the lower jaw 190 extends rearwardly slightly beyond the vertical plane of the upper jaw 215 when the jaws 190 and 215 are in the horizontal position shown in Figure 7. Moreover, the leading upper edge of the lower jaw 190 is beveled, as at 220, to further insure that the leading edge of the carton directed thereto will ride up this beveled surface 220 and will thus be positioned properly between the upper and lower jaws 215 and 190, respectively.

The upper or movable jaw 215 is normally urged downwardly or toward the stationary jaw 190 by a tension spring 221, the upper end of which is connected to a spring anchor 222 extending from an upwardly projecting portion 223 integral with the movable jaw support 213. The movable jaw support 213 is provided with an opening 224 therethrough and the jaw 190 as well as the support bracket 192 therefor are also provided with coinciding openings 225 therethrough. The tension spring 221 extends downwardly from the spring anchor 222 in Figure 7 and through the openings 224 and 225 and the lower end thereof is connected to a suitable spring anchor 226 projecting from the downwardly extending flange portion 192a of the stationary jaw support bracket 192.

The flange portion 192a of the bracket 192 has a pin 227 projecting therefrom on which the lower end of a toggle link 230 is pivotally mounted. This toggle link 230 extends upwardly or towards

12

the movable jaw support bracket 213 and is pivotally connected as at 231 to the proximate end of a second toggle link 232. The end of the toggle link 232 remote from the link 230 is pivotally connected, as at 233, to the upper or movable jaw support bracket 213. It will be observed in Figure 8 that the pivotal connection between the toggle links 230 and 232 has a roller 234 rotatably mounted thereon which is adapted to be engaged, by means to be presently described, for moving the proximate ends of the toggle links 230 and 232 in one direction or the other beyond dead-center.

It will be observed in Figure 7 that the roller 234 is shown positioned beyond dead-center relative to the free ends of the stationary and movable jaws 190 and 215 and the tension spring 221 tends to urge the proximate ends of the toggle links 230 and 232 forwardly to where at least one of the toggle links will engage a stop pin 235 projecting from the bracket 192. This causes the jaws 190 and 215 to remain in a substantially opened position, that is, to remain spaced apart from each other so as to permit the corresponding edge of a carton to be positioned therebetween in the manner heretofore described.

It is evident that, upon the proximate ends of the toggle links 230 and 232 being moved from left to right in Figure 7 beyond dead-center, the movable jaw 215 will be caused to move to closed position by virtue of the tension spring 221.

Now, as the carton C-1 is positioned on the carton positioning plate 135 in the manner heretofore described, the leading edge of the carton 35 is positioned between the movable and stationary jaws 215 and 190, respectively, whereupon the roller 234 is engaged by the lower portion of a first jaw actuating arm 240 which is fixedly mounted on one end of a transverse shaft 241. 40 This shaft 241 is rotated a partial revolution in a counterclockwise direction in Figure 7, by means to be presently described, and causes the first jaw actuating arm 240 to move in a like manner. Thus, the arm 240 engages the roller 45 234 and moves the proximate ends of the toggle links 230 and 232 rearwardly beyond dead-center whereupon the upper or movable jaw 215 will move to closed position by the spring 221 in order to clamp the corresponding edge of the 50 carton previously positioned between the jaws 190 and 215.

The stub shaft 241 is oscillatably mounted in a bearing block or bracket 243 which is secured to the lower surface of the transverse frame member 13, by any suitable means such as bolts 55 244. This bearing block or bracket 243 also extends forwardly and the upper end of the vertically disposed dovetailed guide member 197 is suitably secured to the front end of the bracket 60 243 as by a screw 245 (Figure 3).

Referring to Figure 9, it will be observed that the end of the stub shaft 241 remote from the end on which the arm 240 is fixedly mounted, has an eccentric arm 246 fixedly mounted thereon to the outer end of which the upper end of a connecting rod or link 247 is pivotally connected, as at 250. This link 247 extends downwardly and is pivotally connected to the free end of a corresponding eccentric arm 251 (Figures 1 and 6) which is fixedly mounted on one end of a shaft 252 which is oscillatably mounted in bearing blocks 253. The bearing blocks 253 are integral with or welded to a plate 249 which is suitably secured, as by screws 254, to the upper surface of the transverse frame member 16.

The shaft 252 extends outwardly and also has another eccentric arm 255 fixedly mounted thereon to the free end of which the upper end of a longitudinally adjustable link or connecting rod 256 is pivotally connected, as at 257 (Figure 9). It will be observed in Figure 5 that the lower end of the connecting rod or link 256 is pivotally connected, as at 262, to the free end of one arm of a bell crank 263 which is oscillatably mounted on a stub shaft 264 projecting from and being suitably secured to the side frame member 11. The arm of the bell crank 263 remote from the arm to which the connecting rod 257 is pivotally connected has a cam follower 265 projecting laterally therefrom which engages the periphery of a cam wheel broadly designated at 266 which is provided with diametrically opposed raised portions 267 integral therewith. This cam wheel 266 is fixedly mounted on the cam shaft 27 heretofore described.

The end of the shaft 252 remote from the end on which the eccentric arm 255 is fixedly mounted has a substantially inverted L-shaped second jaw actuating member 270 (Figures 4, 5, 6 and 9) fixedly mounted thereon which extends upwardly therefrom and the upper end of which is adapted to be disposed in the path of the roller 234 at the juncture of the toggle links 230 and 232 (Figure 7) when the grasping unit is moved to a lowered position which is substantially lower than the position shown in Figure 5. The manner in which the carton edge grasping device 150 is raised and lowered will be presently described.

As heretofore described, the grasping device carrier block 196 is mounted for vertical sliding movement on the vertically disposed dovetailed guide member 197, the upper end of the dovetailed guide member 197 being supported by the bracket 243. The lower end of this dovetailed guide bracket is supported by a bracket 275 which is shown in the form of a vertically disposed angle bar and which is suitably secured to the front face of the transverse frame member 16 by any suitable means such as screws 276 (Figure 1).

The angle bar 275 extends substantially above the transverse frame member 16 and is penetrated by a screw 277 which slidably penetrates a spacing member or sleeve 278 and is threadably embedded in the lower portion of the vertically disposed dovetailed guide member 197 (Figure 1). This dovetailed guide member 197 is also provided with a projection 281 at the lower end thereof (Figures 4 and 5) which is threadably penetrated by a stop screw 282 held in adjusted position by a suitable lock nut 283. This stop screw 282 is provided so as to be engaged by the lower surface of the grasping device carrier block 196 when this carrier block 196 has been moved to its lowermost position by means to be presently described.

It will be observed in Figures 5 and 7 that the lower portion of the grasping device carrier bracket 196 is provided with a slot 285, the side walls of which are disposed astride the projection 281 when the bracket 196 is disposed in its lowermost position. Referring to Figure 1, it is evident that the tension spring 203 (Figure 7) normally urges the shaft 194 in a clockwise direction. However, when the grasping device carrier block 196 is in its fully raised position, the follower wheel or roller 206 engages the lower surface of a laterally projecting cam portion 287 (Figures 7, 8 and 9) of a substantially L-shaped

bracket 290 which extends rearwardly and is suitably secured, as by welding, to a bar 291 which is adjustably secured, as by screws 292, to the outer surface of the dovetailed guide member 197.

The bar 291 is provided with elongated slots 293 (Figure 9) which are slidably penetrated by the screws 292 thus facilitating adjustment of the bar 291 and the corresponding L-shaped bracket 292 relative to the dovetailed guide bar 197.

It is evident that this means of adjusting the L-shaped bracket 290 is necessary to insure that the jaws 190 and 215 of the carton edge grasping device may be disposed in a horizontal plane or in parallel relation to the carton positioning plate 135 when the grasping device carrier block 196 is in the elevated position shown in Figure 7.

Since the roller 206 (Figure 7) engages the lower surface of the laterally projecting cam portion 287 of the L-shaped bracket 290 as the block 196 is moved upwardly to fully raised position, this will cause the shaft 194 along with the jaws 190 and 215 of the carton edge grasping device to rotate substantially a quarter revolution in a counter-clockwise direction in Figure 1 to thus cause the lower or stationary jaw 190 to be disposed at substantially the same level as that of the upper surface of the carton positioning plate 135.

Now, as the grasping device carrier block 196 is subsequently moved downwardly, it is evident the tension spring 203 will cause the arm 205 along with the grasping device 150, including the bracket 192, to rotate in a clockwise direction in Figure 1. This rotation of the arm 205 is limited to substantially a quarter revolution because the free end of the arm 205 engages an adjustment screw 295 (Figures 5 and 7) which threadably penetrates an outwardly projecting arm 296 integral with the grasping device carrier block 196. This adjustment screw 295 is locked in adjusted position by a lock nut 297.

It is thus seen that, immediately upon the grasping device carrier block 196 moving downwardly, the corresponding grasping device 150 along with the carton carried thereby will be rotated from a horizontal to a vertical position. Thus, the carton C-1, which is usually made from a flexible material, such as cardboard, when rotated about the axis of the bracket 142, will cause the lower or right-hand end of the carton to be biased slightly so as to move away from above the horizontal leg of the angle bar 146 in Figure 1 and to thus permit the carton to be moved from a horizontal to a vertical position.

As the grasping device carrier block 196 continues to move downwardly, the movable jaw support member 213 is disposed in a vertical position as shown in Figure 5 and, therefore, the roller 234 at the juncture of the toggle links 230 and 232 will be disposed below the corresponding grasping device and, upon the roller 234 moving into the horizontal plane of the second jaw actuating arm 270, one or the other of the raised portions 267 on the cam wheel 266 (Figure 5) engages the cam follower 265 causing the bell crank 263 to move a partial revolution in a counter-clockwise direction. This will cause the connecting rod 256 to move downwardly and, in so doing, will cause the shaft 252 to move in a clockwise direction in Figure 9 or a counter-clockwise direction in Figure 5. This moves the upper end 70 of the second jaw actuating arm 270 forwardly

whereupon this arm 270 engages the roller 234 and causes the toggle links 230 and 232 to move forwardly or to substantially the position shown in Figure 7.

This will cause the movable jaw 215 to move away from the stationary jaw 190 to thus release the carton from the grasping device 150. The means for moving opposed sides of the carton apart from each other, which means is represented by the grasping devices 36 and 37 in Figures 5 and 4 will then move inwardly to engage the outer surfaces of the flaps of the carton to thus move the flaps of the carton apart from each other in the manner described in said Patent No. 2,603,924. The carton edge grasping device 150 will then immediately be elevated again to the position substantially as shown in Figures 7 and 9 and, at the same time, the jaws will be moved to the horizontal position shown in Figures 7 and 9 because of the roller 206 again moving into engagement with the laterally extending portion 287 of the L-shaped bracket 290.

It will be noted that both the first and the second jaw actuating members 240 and 270 are operated simultaneously although only one of these arms is effective at one time since the arm which is effective will depend upon whether the grasping device 150 is in an elevated or lowered position.

Therefore, it is evident that one or the other of the raised portions 267 on the cam wheel 266 (Figure 5) moves into engagement with the cam follower 265 immediately before the bracket 192 assumes a fully raised position and as this same raised portion 267 on the cam wheel 266 moves out of engagement with the cam follower 265, the arm 240 will move rearwardly or in a counter-clockwise direction in Figure 7 to thus again permit the tension spring 221 to move the movable jaw 215 to closed position. The length of arc of the raised portion 257 on the cam wheel 266 is such that the carton from the hopper 50 will have had ample time to be admitted to the jaws 190 and 215 of the grasping device 150 before the movable jaw 215 is moved to closed position.

Now, in order to raise and lower the grasping device carrier block 196 in timed relation to operation of the grasping device 150, the lower end of a link 300 is pivotally connected to the block 196 as at 301. This link 300 extends upwardly in Figures 1, 2, 5 and 7 and is pivotally connected, as at 302, to the lower end of the substantially vertical leg of a substantially L-shaped carrier block positioning arm 303.

This arm 303 is shown as being L-shaped but it is evident that this arm 303 may extend outwardly and the link 300 could be relatively longer than is shown in the drawings and thus connected to the free end of the arm 303. The arm 303 extends rearwardly and is fixedly mounted on a shaft 305 which is rotatably mounted in laterally spaced bearing blocks 306 (Figure 3) suitably secured, as by screws 307 (Figure 5), to the transverse bar 53 to which the bars 51 forming the front wall of the hopper 50 are secured.

The shaft 305 extends outwardly beyond the outermost of the bearing blocks 306 and has one end of an arm 310 fixedly mounted thereon. This arm 310 extends forwardly and has the upper end of a longitudinally adjustable connecting rod or link 311 pivotally connected thereto, as at 312 (Figure 5). It will be observed in Figure 5 that the lower end of this connecting rod 311 is pivotally connected, as at 313, to one arm of a bell

crank 314, the other arm of which has a cam follower 315 projecting therefrom. This cam follower 315 is normally urged into engagement with a cam wheel 316 by a tension spring 317 (Figure 2), the upper end of which is suitably connected to the free end of the arm 310 and the lower end of which is suitably connected to the side frame member 11. The cam wheel 316 is fixedly mounted on the driven cam shaft 27 heretofore described.

It is thus seen that upon the low point of the cam 316 moving into engagement with the cam follower 315, the bell crank 314 is urged in a clockwise direction, in Figure 5, by the tension spring 317. This will, in turn, cause the grasping device carrier block 196 to move downwardly until it engages the upper surface of the stop screw 282 in Figure 5. Now, the spring 317 will urge the block 196 into engagement with the upper surface of the stop screw 282 although the low point of the cam 316 may normally permit the cam follower 315 to move further in a clockwise direction in Figure 5.

This will insure that the carton C-1 is accurately positioned so that, when the side flaps of the carton are moved apart from each other by the grasping devices 36 and 37, this carton will be properly positioned for reception of the articles admitted thereto by the elevating means heretofore described. It is evident that upon the higher portion of the cam wheel 316 moving into engagement with the cam follower 315, the free end of the arm 310 will be moved upwardly in Figure 5, in the opposite direction from that in which it is biased by the tension spring 317, to thus move the grasping device carrier block 196 from lowered to raised position.

It is evident that vertical movement of the grasping device carrier block 196 and rotation of the carton positioning plate 135 is such that the free end of the carton positioning plate 135 will move downwardly to a vertical position as the grasping device carrier block 196 is moved downwardly to substantially the position shown in Figure 1 thus insuring that the plate 135 will clear the carton C-1 as the carton is rotated about the axis of the shaft 194.

It is thus seen that we have provided an improved means for successively positively feeding the empty cartons from the hopper to a position between the grasping devices 36 and 37 and wherein the cartons are moved, one at a time, from the hopper, with the cartons positioned in a horizontal plane, to a position above the means for moving the opposed sides of the carton apart from each other and then the particular carton positioned above the means for moving both sides thereof apart from each other is rotated about an axis midway of the carton and then moved forceably downward to an accurately predetermined position whereupon the means for moving the carton downwardly releases the carton and returns to its original position for reception of another carton as the opposed sides of the previous carton are moved apart from each other for reception of the articles.

In the drawings and specification, there has been set forth a preferred embodiment of the invention and although specific terms are employed, they are used in a generic and descriptive sense only and not for purposes of limitation, the scope of the invention being defined in the claims.

We claim:

1. An improvement in a machine for positioning articles, such as bottles and the like, in car-

tons, said machine having means for moving opposed sides of a normally flat carton apart from each other and also having a hopper disposed above and to one side of the means for moving opposed sides of the carton apart from each other, said improvement comprising means for positioning a single carton at a time above the means for moving opposed sides of the carton apart from each other, means for gripping the edge of the carton and rotating the carton so positioned about an axis transverse of the carton and intermediate the upper and lower ends of said carton to thus rotate the carton from a horizontal to a vertical position, and mechanically operable means for moving the carton downwardly a predetermined distance for positioning said carton between the means for moving opposed sides of the carton apart from each other.

2. An improvement in a machine for placing articles in cartons, said carton being of a type having side flaps normally positioned in juxtaposed relation to each other, said machine having a hopper in which the cartons are adapted to be stacked in a horizontal position and said machine also having a means spaced below and to one side of the vertical plane of said hopper for moving the flaps on opposed sides of a carton positioned therebetween apart from each other, said improvement comprising positive means for transferring the cartons from the hopper, one at a time, to a position between the means for moving opposed side flaps of the carton apart from each other comprising a carton positioning plate normally disposed in a horizontal position adjacent the hopper and spaced above the means for moving opposed side flaps of the carton apart from each other, means operable automatically for moving the lowermost carton in the hopper onto said carton positioning plate, a vertically movable and horizontally rotatable carton edge grasping means disposed adjacent the edge of said carton positioning plate remote from the edge adjacent which the hopper is disposed, means on the grasping device for grasping the corresponding edge of the carton as it is admitted to the carton positioning plate, means operable automatically upon the carton being positioned on said carton positioning plate for actuating the grasping means for grasping the corresponding edge of said carton, means operable automatically upon said grasping device being actuated for simultaneously moving the carton positioning plate away from the lower surface of the carton previously positioned thereon and for rotating the carton edge grasping device substantially a quarter revolution for moving a corresponding carton from a horizontal to a vertical position, means operable automatically as the carton is being moved from a horizontal to a vertical position for moving the carton edge grasping device downwardly a predetermined distance to thereby position the carton carried thereby between the means for moving the side flaps of the carton apart from each other, and means operable automatically upon said carton edge grasping device moving said predetermined distance for releasing the carton from the carton edge grasping device whereby the means for moving the side flaps of the carton apart from each other may perform the latter operation.

3. In a structure according to claim 2, said carton edge grasping device comprising a stationary jaw and a movable jaw cooperatively interconnected and extending in parallel relation to each other, the upper surface of at least one

of said jaws normally extending in a horizontal plane in substantially the same horizontal plane as the carton positioning plate for reception of the corresponding edge of the carton as it is admitted to the carton positioning plate, means operable automatically upon said carton being positioned between the movable and stationary jaws of the carton grasping device for moving the movable jaw to a closed position and for clamping the corresponding edge of the carton between the movable and stationary jaws, means operable automatically upon said jaws being moved to closed position for rotating the jaws about a common axis for substantially a quarter revolution and simultaneously moving the carton positioning plate downwardly and out of the vertical plane of the carton previously positioned thereon to thus move the carton from a horizontal to a vertical position, means operable automatically for simultaneously moving the stationary and movable jaws from a raised to a lowered position adjacent the means for moving the opposed side flaps of the carton apart from each other and means operable automatically upon said jaws being moved to a lowered position for again moving the movable jaw away from the stationary jaw for releasing the carton therefrom to be operated upon by the means for moving the opposed side flaps of the carton apart from each other.

4. An improvement in a machine for positioning articles in cartons, said machine having a station at which a group of articles are adapted to be positioned in a carton and also having a hopper disposed at a different level than said station and to one side of the vertical plane of said station and in which a plurality of cartons are adapted to be stacked in superposed relation to each other, said machine also having means for directing a single carton at a time horizontally from the hopper to a position in vertical alignment with said station and means for opening the cartons for reception of said articles, said improvement comprising means for gripping and rotating each carton successively positioned in the vertical plane of the station substantially a quarter revolution about a horizontal axis to thus rotate the carton from a horizontal to a vertical position and mechanically operable means for moving the carton from the level of the hopper to the level of the station for positioning said carton for reception of said group of articles.

5. An improvement in a machine for positioning articles in cartons, said machine having a station at which a group of articles are adapted to be positioned in a carton and also having a hopper disposed at a different level than said station and to one side of the vertical plane of said station and in which a plurality of cartons are adapted to be stacked in superposed relation to each other, said machine also having means for directing a single carton at a time horizontally from the hopper to a position in vertical alignment with said station and means for opening the cartons for reception of said articles, said improvement comprising means for rotating each carton successively positioned in the vertical plane of the station substantially a quarter revolution about a horizontal axis to thus rotate the carton from a horizontal to a vertical position, mechanically operable means for moving the carton from the level of the hopper to the level of the station for positioning said carton for reception of said group of articles

and means operable automatically upon said carton being positioned at said station for releasing the carton from the mechanically operable means for moving the carton and then returning said mechanically operable means to its original position at the level of the hopper.

6. In a machine for positioning articles in cartons, said machine having a station at which a group of articles are adapted to be positioned in a carton and also having a hopper disposed at a different level than said station and to one side of the vertical plane of said station and in which a plurality of cartons are adapted to be stacked in superposed relation to each other, said machine also having means for directing a single carton at a time horizontally from the hopper to a position in vertical alignment with said station and means for opening the cartons for reception of articles; a pivoted carton positioning plate normally disposed in a horizontal plane adjacent the hopper and onto which each carton is successively moved by said means for directing a single carton at a time to a position in vertical alignment with said station, normally open carton edge clamping means disposed in the path of the leading edge of each carton as it is directed onto the carton positioning plate, first cam controlled means for closing said carton edge clamping means to cause the corresponding edge of the carton to be clamped by said carton edge clamping means, second cam controlled means for rotating the carton positioning plate from a horizontal to a vertical position to one side of the vertical plane of said station, means operable automatically upon said carton edge clamping means clamping the carton for rotating the carton edge clamping means about a horizontal axis for substantially a quarter revolution to thereby move the carton from a horizontal to a vertical attitude, a third cam controlled means for moving the carton edge clamping means from the level of the hopper to the level of said station, and means responsive to said second cam controlled means for releasing the carton from said carton edge clamping means upon the carton edge clamping means being moved to the level of said station, whereby, upon said carton edge clamping means releasing said carton therefrom, the carton will then be positioned for reception of said group of articles.

7. An improvement in a machine for positioning articles such as bottles, cans, and the like in cartons, said machine having means for moving opposed side flaps of a normally flat carton apart from each other, and also having a hopper disposed above and to one side of the means for moving opposed side flaps of a carton apart from each other, said improvement comprising means for positioning a single carton at a time above the means for moving opposed side flaps of a carton apart from each other, mechanical means for rotating the carton so positioned about an axis transversely of the carton for substantially a quarter revolution to thus rotate the carton from a horizontal to a vertical position and a first cam controlled means for moving the carton downwardly a predetermined distance for positioning said carton between the means for moving opposed side flaps of the carton apart from each other.

8. In a structure according to claim 7, mechanical means for rotating the carton comprising normally horizontally disposed first and second relatively movable jaws, a horizontally disposed shaft on which said relatively movable jaws are

mounted, a vertically movable carrier block, guide means on the machine for supporting the vertically movable carrier block for sliding movement thereon, said shaft being rotatably mounted in the carrier block, stationary cam means carried by the machine for normally holding the jaws in said horizontal position, a second cam controlled means for moving said jaws to a closed position upon the corresponding edge of a carton being positioned therebetween, means responsive to said first cam controlled means for moving the carrier block from a raised to a lowered position, spring means urging the jaws from a horizontal to a vertical position as the carrier block moves downwardly away from said stationary cam means for rotating the carton carried by the jaws from a horizontal to a vertical position and said second cam controlled means also being operable automatically upon said carton being moved downwardly a predetermined distance to a position adjacent the means for moving opposed side flaps of the carton apart from each other for opening said jaws to release the carton therefrom.

9. In a structure according to claim 8, said first cam controlled means also being operable automatically upon said carton being released from said jaws for returning the carrier block to its original position.

10. An improvement in a machine for positioning articles such as bottles, cans and the like in cartons, said machine having means for moving opposed side flaps of a normally flat carton apart from each other, and also having a hopper disposed above and to one side of the means for moving opposed side flaps of a carton apart from each other, said improvement comprising means for positioning a single carton at a time above the means for moving opposed side flaps of a carton apart from each other, mechanical means for rotating the carton so positioned about an axis transversely of the carton for substantially a quarter revolution including normally horizontally disposed relatively movable first and second jaws, a vertically movable carrier block, guide means on the machine for supporting the vertically movable carrier block for sliding movement thereon, a horizontally disposed shaft rotatably mounted in said carrier block and on which the relatively movable jaws are mounted, spring means normally urging said jaws to a vertical position, means for holding said jaws in a horizontal position while said jaws are at the same level as said hopper, means operable automatically for moving said jaws to a closed position upon said carton being moved to a position above the means for moving opposed side flaps of a carton apart from each other, means operable automatically for moving the carrier block to a lowered position upon said jaws being moved to a closed position, and means operable automatically for opening said jaws to release the carton therefrom upon said carrier block being lowered to a predetermined position, whereby said carton is rotated from a horizontal to a vertical position upon being moved from above the means for moving opposed side flaps apart from each other to the level of said last-named means.

11. An improvement in a machine for positioning articles such as bottles, cans and the like in cartons, said machine having means for moving opposed side flaps of a normally flat carton apart from each other, and also having a hopper disposed above and to one side of the means

for moving opposed side flaps of a carton apart from each other, said improvement comprising means for positioning a single carton at a time above the means for moving opposed side flaps of a carton apart from each other, mechanical means for rotating the carton so positioned about an axis transversely of the carton for substantially a quarter revolution including normally horizontally disposed relatively movable first and second jaws, a vertically movable carrier block, 10 guide means on the machine for supporting the vertically movable carrier block for sliding movement thereon, a horizontally disposed shaft rotatably mounted in said carrier block and on which the relatively movable jaws are mounted, 15 spring means normally urging said jaws to a vertical position, means for holding said jaws in a horizontal position while said jaws are at the same level as said hopper, means operable automatically for moving said jaws to a closed position upon said carton being moved to a position above the means for moving opposed side flaps of a carton apart from each other, means operable automatically for moving the carrier 20 block to a lowered position upon said jaws being moved to a closed position, means operable automatically for opening said jaws to release the carton therefrom upon said carrier block being lowered to a predetermined position, whereby 25 said carton is rotated from a horizontal to a vertical position upon being moved from above the means for moving opposed side flaps apart from each other to the level of said last-named means, a carton positioning plate disposed in the same horizontal plane as the lowermost of the 30 relatively movable first and second jaws while in a raised position for supporting each carton as it is positioned above the means for moving opposed side flaps apart from each other and means operable automatically for moving said carton 35 positioning plate away from beneath the carton previously positioned thereon upon said carton being clamped between the first and second jaws.

12. An improvement in a machine for positioning articles such as bottles, cans and the like in cartons, said machine having means for moving opposed side flaps of a normally flat carton apart from each other, and also having a hopper disposed above and to one side of the means for moving opposed side flaps of a carton apart from each other, said improvement comprising means for positioning a single carton at a time above the means for moving opposed side flaps of a carton apart from each other, mechanical means for rotating the carton so positioned about an 40 axis transversely of the carton for substantially a quarter revolution including normally horizontally disposed relatively movable first and second jaws, a vertically movable carrier block, 45 guide means on the machine for supporting the vertically movable carrier block for sliding movement thereon, a horizontally disposed shaft rotatably mounted in said carrier block and on

which the relatively movable jaws are mounted, spring means normally urging said jaws to a vertical position, means for holding said jaws in a horizontal position while said jaws are at the same level as said hopper, means operable automatically for moving said jaws to a closed position upon said carton being moved to a position above the means for moving opposed side flaps of a carton apart from each other, means operable automatically for moving the carrier block to a lowered position upon said jaws being moved to a closed position, means operable automatically for opening said jaws to release the carton therefrom upon said carrier block being lowered to a predetermined position, whereby said carton is rotated from a horizontal to a vertical position upon being moved from above the means for moving opposed side flaps apart from each other to the level of said last-named means, a carton positioning plate disposed in the same horizontal plane as the lowermost of the relatively movable first and second jaws while in a raised position for supporting each carton as it is positioned above the means for moving opposed side flaps apart from each other, and cam controlled means for moving said carton positioning plate away from beneath the carton previously positioned thereon upon said carton being clamped between the first and second jaws.

13. In a structure according to claim 12, a horizontally disposed guide member disposed adjacent one edge of the carton positioning plate and means for urging the corresponding edge of the carton against said guide member upon the carton being directed onto the carton positioning plate to thereby insure that the carton is accurately positioned between the first and second jaws transversely of the axis of the shaft supporting said jaws.

14. In a machine for positioning articles, such as bottles and the like, in cartons, said machine having means for moving opposite sides of a normally flat carton apart from each other and means for storing a plurality of superposed cartons remote from said first means; mechanical feeding means for moving a single carton at a time from said storage point, mechanical means for gripping one edge of said carton and partially rotating the same, and said last-named means also being operable to move said carton between said means for moving the opposite sides of the carton apart for reception of articles.
